(57) **CLAIM**

The ornamental design for a decorative candleholder, as shown and described.

DESCRIPTION

FIG. 1 is an isometric view of a decorative candleholder showing our new design;

FIG. 2 is a front elevational view of the decorative candleholder of FIG. 1;

FIG. 3 is a right elevational view of the decorative candleholder of FIG. 1;

FIG. 4 is a left elevational view of the decorative candleholder of FIG. 1, the rear elevational view being identical thereto;

FIG. 5 is a top plan view of the decorative candleholder of FIG. 1;

FIG. 6 is an isometric view of yet another decorative candleholder according to the present invention;

FIG. 7 is a front elevational view of the decorative candleholder of FIG. 6;

FIG. 8 is a right elevational view of the decorative candleholder of FIG. 6, the left and rear elevational views being identical thereto; and,

FIG. 9 is a top plan view of the decorative candleholder of FIG. 6.

Portions shown in dashed lines are not part of the claimed design.
